DESIGN FOR A VENDING MACHINE CON- TENTS DISPLAY PANEL

Warren B. Green, New York, N. Y., assignor to
U-Need-A-Pak Products Corp., Brooklyn, N. Y.,
a corporation of New York

Application December 11, 1940, Serial No. 97,253

Term of patent 3½ years

To all whom it may concern:

Be it known that I, Warren B. Green, a citizen of the United States and resident of the city, county, and State of New York, have invented a new, original, and ornamental Design for a Vending Machine Contents Display Panel, of which the following is a specification, reference being had to the accompanying drawing, forming a part thereof.

Fig. 1 is a front elevational view of a vending machine contents display panel embodying my new design.

Fig. 2 is an enlarged cross-sectional view on the line 2—2 of Fig. 1.

Fig. 3 is an enlarged fragmentary portion of the lower part of the panel, showing the con-

trasting appearance between mirrored and transparent portions.

The characteristic features of my design reside in the provision of a mirrored panel having formed at the lower portion thereof a plurality of merchandise exposing areas, each of said areas being transparent at the lower part thereof and being provided at the upper part thereof with a plurality of alternate mirrored and transparent areas.

I claim:

The ornamental design for a vending machine contents display panel, substantially as shown and described.

WARREN B. GREEN.
